UNITED STATES PATENT OFFICE.

JOSEPH S. DUNCAN, OF CHICAGO, ILLINOIS, ASSIGNOR TO ADDRESSOGRAPH COMPANY, OF CHICAGO, ILLINOIS, A CORPORATION OF ILLINOIS.

RIBBON-SPOOL MOUNTING.

Application filed May 29, 1922. Serial No. 564,339.

To all whom it may concern:

Be it known that I, JOSEPH S. DUNCAN, a citizen of the United States, residing at Chicago, in the county of Cook and State of Illinois, have invented certain new and useful Improvements in Ribbon-Spool Mountings, of which the following is a specification.

This invention relates to printing machines which make an impression through an ink ribbon and it has reference more particularly to the means for mounting the ribbon spool in the machine.

The object of the invention is to provide means whereby a ribbon spool may be easily and quickly mounted in operative position in a machine without requiring any special manipulation or any loose parts or any special adjustments.

20 A further object of the invention is to provide means for readily adapting the mounting to receive spools of different lengths.

In the accompanying drawings I have illustrated so much of a machine as is necessary for an understanding of the invention and referring thereto

Fig. 1 is a plan view showing the machine frame partly in section;

30 Fig. 2 is also a plan view, on a smaller scale than Fig. 1, showing a spool supporting bracket slid to one side of printing position and parts of the frame in section;

Fig. 3 is an elevation looking at the left end of Fig. 1;

Fig. 4 is a transverse section on the line 4—4 of Fig. 1;

40 Figs. 5 and 6 are longitudinal sections on the lines 5—5 and 6—6 respectively of Fig. 1;

Fig. 7 is a view similar to Fig. 1 showing a smaller spool and an extension made therefor;

Fig. 8 is a sectional view on the line 8—8 of Fig. 7;

Fig. 9 is a plan view on a reduced scale showing the two ribbon spools and their mountings with the ribbon stretched between the spools;

50 Fig. 9^a is a sectional view on the line 9^a—9^a of Fig. 9.

Fig. 10 is a longitudinal sectional view of a portion of a ribbon spool, and Fig. 11 is an end view of the spool forming the subject matter of my co-pending application,

Serial No. 564,340, filed May 29, 1922, which can be used with this invention.

Referring to the drawings, 10—10 are two brackets arranged to slide on tracks or rails 11—11 supported in the frame 12 of the machine. I have employed the present invention with satisfactory results in a machine for printing letters from a stationary form and individual addresses for each printed letter from successively changing address forms, one of which is fed to printing position for each printing operation so that a letter and a different address is printed at each operation of the machine. The invention may be employed with machines designed to print from a stationary form only or it may be embodied in any other type of printing machine for which it is adapted. The part 12 may be the main frame of the printing machine or any other part thereof forming a support for the ribbon spool mounting herein described.

A shaft 13 (Figs. 1—5) is supported in a part of the frame 12 and a head 14 is removably secured on the end of the shaft 80 by a pin 14'. A knurled head 15 and a ratchet wheel 16 are spaced apart and pinned to the shaft 13 and between them a lever is intermediately mounted, one arm 17 thereof carrying a spring controlled feed 85 pawl 18 which engages the ratchet wheel 16, and the other arm 17' of the lever being connected to an operating rod 19 which is operated in any suitable manner to impart an intermittent motion to the shaft 13 and thereby cause the ribbon spool 20 to revolve in the usual feeding or take up motion. The knurled head is provided to enable a manual movement of the ribbon spool whenever required.

The bracket 10 (Figs. 1, 2 and 6) is provided with lugs 12' which support a rod 21 slidably mounted therein and having at one end a head 22 which may be keyed to the rod, as shown in Fig. 6, to revolve independently thereof, or it may be pinned rigidly to the rod to remain stationary therewith. A knurled head 23 is pinned to the other end of the rod 21 and adjacent to the knurled head an arm 24 is rigidly mounted on the rod and carries a pin 25 which is adapted to be engaged with an opening 25' in the lug 12', or with a recess 25''. The arm 24 is also provided with a handle 24'. A spring 26 on the rod 21 normally 105

holds the rod projected with the head in operative engagement with the spool 20 and the pin 25 engaged with the opening 25' which prevents rotation of the rod 21. If 5 the head 22 is keyed to the rod 21 as shown, it may revolve intermittently with the spool 20 which is driven from the mounting at the other end of the spool, as hereinbefore described, but if the head 22 is pinned 10 rigidly to the rod the spool will revolve in the head. When it is desired to release the clamping action of the heads 14 and 22 on the spool for any purpose it may be easily accomplished by grasping the knurled head 15 23 and withdrawing the rod, compressing the spring 26, withdrawing the head 22 from the spool 20 and withdrawing the pin 25 from the opening 25'. To hold the rod 21 in this position the rod is turned sufficiently, 20 by manipulating the head 23 or the handle 24', to engage the pin 25 with the recess 25".

The machine will ordinarily be constructed for making impressions from a printing form of certain predetermined maximum 25 dimensions, and the spool mounting will be made accordingly to receive spools carrying a ribbon of a width suitable for such a form; but it may be desirable to use a smaller form in such a machine, requiring 30 a correspondingly smaller ribbon and I have provided means for extending the heads to accommodate shorter spools. I have only shown one such extension in the drawings but it will be understood that a plurality of 35 extensions of different lengths may be provided if desired. In Figs. 7 and 8 the extension head 27 is substituted for the head 14 and pinned to the shaft 13 and the spool 27' is engaged with the extension head as heretofore described. A corresponding extension head will be provided for the companion spool (not shown).

The mounting for the companion spool 20' is substantially the same as the mounting 45 for the spool 20 except that the feed mechanism is not required and the left end head 28 is mounted on an arm 29 adjustably secured by set screws 30-30' which engage 50 openings 30'-30" in the bracket 10' to slide therewith. Since this head is not directly driven it can be made adjustable in this manner and the extension head or adapter 55 27 required for extending the head 14 is not necessary.

To support the spool 20 in position for being clamped between its heads I provide 60 guides in the form of pins 31 mounted on arms 32-32' carried by the bracket 10 (Fig. 2), one of these arms being adjustably mounted on the bracket 10 to conform with the adapter extension when used (Figs. 1-7). Between each pair of pins 31 I provide a short pin 31' upon which the spool rests 65 temporarily. For the other spool 20' I provide at the right end an arm 33 with guide

pins 34 and supporting pin 34' similar to those heretofore described, and I would employ the same guide and supporting pins at the left end of this spool 20' if desired but I have found it convenient to use here a 70 yoke 35 which is secured by screws to the arm 29 and is adjustable therewith.

I prefer to make the heads for the left end (Fig. 5) of each spool with a groove 75 36 and with a conical projecting center 37 (Fig. 5); and the head on the adapter extension 27 is similarly provided with a groove 36' and the center conical extension 37' (Fig. 8). The heads at the right hand ends of the spools (Fig. 9) are preferably recessed at 38 (Fig. 6) to receive the 80 ends of the spools. The right heads being withdrawn and secured in retracted position, as heretofore described, the spools are inserted in place and rest between the guide pins 31 resting upon the supporting pins 31'. The left end of the spool 20' will rest in the yoke 35. The left ends of both spools are hollow (the spools being ordinarily tubular) and engage the conical centers of the left heads. When the right heads are released from retracted position the springs 26 project them forwardly engaging the right ends of the spools and forcing the spools into the grooves 36 in the left heads, the spools being guided by the conical centers 37-37' in this movement. The inner wall of the flange forming the grooves of the left heads and the inner wall of the flange forming the recesses in the right heads are bevelled so that when the heads are clamped on the spool the latter will be lifted sufficiently to clear the full spool from the support 31' and the yoke. Ordinarily this lifting will be important only as to the spool 20' which is inserted 90 fully wrapped as the ribbon supply spool, the outer end of the ribbon being fastened or to be fastened to the spool 20 which is the feed or windup spool. But it may be necessary or desirable at any stage of the operations to remove and to replace the ribbon as it was when removed and I therefore find it convenient to provide for supporting the spools as heretofore described. 100

I may construct the spool ends and the heads, one or both, for frictional or for interlocking engagement, but it is only essential that the left head 14 for the spool 20 should have driving engagement, frictional or interlocking, with the spool; the other heads may revolve freely with the spools or they may be relatively stationary and the spools revolve freely therein. For this interlocking engagement I may provide the driving head 14 (and also the other heads if desired) with serrations 38 and one or both ends of each spool with serrations 39 radially disposed for making interlocking engagement to drive the spool, (Figs. 4-5) 110

or I may provide one or both ends of the spools with teeth 40 extending longitudinally in the direction of the length of the spool to make interlocking engagement with recesses 41 forming teeth 42 therebetween for interlocking engagement with the teeth on the spool to drive the spool (Figs. 10, 11). I prefer to have some interengaging parts on the spool and head for interlocking them to produce a positive as distinguished from a frictional driving connection, since this will assure a proper intermittent feed of the ribbon and avoid the possibility of slipping which may occur with a friction drive. For some purposes, it may be sufficient to provide for a friction drive.

It is necessary, of course, that spool 20 should be supported when the brackets 10-10 are moved to the right (as indicated at Fig. 2) to permit access to the printing form which is ordinarily covered by the ribbon because the driven head 14 must remain in fixed position, and this support is furnished by pins 31' in cooperation with the guide pins 31.

The invention provides a simple mounting for the ribbon spools in the machine and I prefer that the spools should be made so that either spool may be arranged in the mounting for spool 20 and so that the position of the spools may be reversed to reverse the ribbon.

The embodiment of the invention shown in the drawings is a selected form which I have found satisfactory, but I am aware that changes in the form, proportion and arrangement of parts may be made without departing from the spirit or sacrificing the advantages of the invention and I reserve the right to make all such changes as fairly fall within the scope of the following claims.

I claim:

1. The combination of a driving head and

a clamping head, means for operating the driving head, a spring pressed rod carrying 45 the clamping head, a ribbon spool, comprising a tubular member, seats in each of said heads to receive the ends of said tubular member, and means on the driving head and on the end of the tubular member engaged 50 therewith for making interlocking driving connection therebetween.

2. The combination of a ribbon spool, a spring pressed rod, a support for said rod having an opening therein and a recess adjacent said opening, a head carried by the rod and engaging the end of the spool, an arm on the rod, and a pin carried by the arm and engaging said opening in the forward position of the head and adapted to engage 60 said recess to hold the arm and head in retracted position.

3. The combination of a slidable supporting member, arms on said supporting member, and devices spaced apart on said arms 65 to receive a ribbon spool therebetween and form a guide therefor.

4. The combination of a supporting member, arms on said supporting member, one of said arms being movable relatively to the 70 other, and uprights spaced apart on said arms and adapted to receive a ribbon spool therebetween and form a guide therefor.

5. The combination of a slidable supporting member, arms on said supporting member, and devices on said arms to receive and 75 form supports for a ribbon spool before it is clamped in operative position.

6. The combination of a supporting member, arms on said supporting member, pins 80 spaced apart on said arms to form guides for a ribbon spool, and devices arranged on the arms between the pins to form supports for said spool.

JOSEPH S. DUNCAN.
